UNITED STATES PATENT OFFICE.

HENRY H. EBAUGH, OF HEREFORD, MARYLAND.

IMPROVEMENT IN MUCILAGE-BOTTLES.

Specification forming part of Letters Patent No. 75,672, dated March 17, 1868.

To all whom it may concern:

Be it known that I, HENRY H. EBAUGH, of Hereford, in the county of Baltimore and State of Maryland, have invented an Improved Fountain Mucilage Can or Holder; and I do hereby declare that the following is a full and exact description thereof, reference being had to the accompanying drawing, making part of this specification, and representing a central vertical section of the can.

The body A of the can may be of any convenient or desirable form, and is made airtight in all parts except where the opening in the top is made for the fountain-tube, and a vent, *a*, for the purpose of letting out the air in filling. This vent-aperture may be very small, and ordinarily closed by a bit of sealing-wax or a plug; or it may be larger and closed with a screw-cap or a stopper, and used, when required, for filling through.

The fountain-tube B is made sufficiently broad at the upper end, *b*, to readily insert and withdraw the brush without touching it and smearing its surface with the mucilage. The lower end, *c*, however, is quite small, substantially as shown, so as to compress the brush somewhat as it is withdrawn, and thereby prevent its taking up too much of the mucilage. It should reach within about half an inch (more or less) of the bottom of the can, so

that the brush C can reach down into and be saturated with the mucilage.

The handle of the brush may terminate in a knob, *d*, at the upper end, with an enlargement or cork or stopper, *f*, to fit and close the top of the fountain-tube.

Thus constructed the fountain-tube B does not fill with the mucilage, although the can may be full, and as the brush takes out the mucilage from the bottom a little air is let into the can, so as to let enough mucilage down to fill up to the bottom of the fountain-tube.

The advantages of this fountain-can are that the mucilage never dries away nor sours by exposure to the air, nor daubs the outlet with the brush, does not spill when the can is overturned, and is not wasted in use.

What I claim as my invention, and desire to secure by Letters Patent, is—

A mucilage can or holder with a fountain-tube, B, in combination with a stoppered brush, constructed and operating substantially as and for the purposes herein specified.

HENRY H. EBAUGH.
